VACUUM TUBE CIRCUIT

Robert D. Duncan, Jr., East Orange, N. J., assignor, by mesne assignments, to Wired Radio, Inc., New York, N. Y., a corporation of Delaware

Application October 20, 1923, Serial No. 669,662

9 Claims. (Cl. 179—171)

This invention has to do with the operation of electron discharge devices, in signaling systems, on alternating current, and its object is to provide an efficient circuit arrangement whereby the filament of such a device can be heated by alternating current with little or no resulting low frequency component in the output circuit of the device.

In the use of alternating current for the purpose stated it has heretofore been the practice to employ what is known as a center point connection from the secondary winding of the filament transformer to the grid or plate or both, the idea being to prevent any fluctuating difference of potential between the filament and either of the other electrodes.

In the practice of the present invention an alternating potential of the same frequency as the filament heating current is applied to one or both of the cold electrodes and the intensity and sometimes the phase relation of the potentials thus applied are so proportioned that the alternating current hum which would otherwise be present in large volume in the output circuit is substantially or completely neutralized.

Generally the filaments of electron discharge devices (vacuum tubes) are designed to operate on relatively low voltage, say 6 volts, and in order to enable them to be operated from the ordinary 110 volt lighting circuits in common use, it is necessary to employ a stepdown transformer.

According to the preferred practice of the present invention, a transformer comprising one or more secondary windings in addition to the usual secondary winding is employed. The additional or supplementary winding or windings are interposed in the circuit between one side of the filament and the grid or plate or both, as the case may be, and are designed to produce the proper alternating potential or potentials which, when applied to the respective electrodes, will produce the desired neutralizing effect. The potentials required for this purpose for each particular type of vacuum tube are best determined by experiment.

It is not necessary that a special transformer having more than one secondary winding be employed, for, as will be clearly explained herein-after, it is practicable to use two or more transformers each having but a single primary and a single secondary winding.

A transformer having a primary and two secondary windings one of which is a supplementary winding and having one or more adjustable air gaps in the magnetic core thereof has been

found to be particularly effective on account of the facility afforded for accurately adjusting the inductive coupling between the primary and secondary winding or windings, thus affording a convenient means for adjusting the intensity of the potentials impressed on the grid or plate or both.

A clearer understanding of the invention may be had from the following detailed description in conjunction with the accompanying drawings, in which

Fig. 1 shows an amplifier circuit comprising two three-electrode vacuum tubes with their filaments arranged to be heated by alternating current, there being provided a transformer having a primary and two secondary windings. In this circuit the potential developed by the additional or supplementary secondary winding is impressed on both the grids and plates of the two vacuum tubes;

Fig. 2 is a circuit similar to Fig. 1 wherein only the plates of the vacuum tubes are connected with the supplementary secondary winding;

Fig. 3 is a modification of the circuit shown in Fig. 1 wherein the grid and plate connections to the supplementary secondary winding are effected through the media of potentiometers connected across the terminals of the supplementary secondary winding;

Fig. 4 is a modification of the circuit shown in Fig. 2 wherein the plate connections of the supplementary winding of the transformer are effected through the medium of a potentiometer connected across the terminals of the supplementary winding;

Fig. 5 shows a single-tube receiving circuit comprising two transformers, one of which is provided for stepping down the voltage for the filament, and the other for furnishing the alternating potential for application to the grid and plate;

Fig. 6 is a two-tube amplifier circuit comprising a transformer having two supplementary secondary windings, one of which is intended to furnish the alternating potential to be applied to the grids, while the other is intended to furnish the alternating potential to be applied to the plates; and

Fig. 7 is a single-tube receiving circuit comprising a transformer having adjustable air gaps.

In the amplifier circuit of Fig. 1 the transformer 1 comprises primary winding 2, which may be associated through its terminals with an antenna or metallic transmission line for receiving incoming signals, and a secondary winding 3 is

connected in the input circuit of vacuum tube 4. Each of the vacuum tubes 4 and 5 comprises a filament or cathode 6, grid or control electrode 7, and plate or anode 8. The filaments 6 are connected in parallel to the terminals of the secondary winding 9 of the transformer 10, the primary 11 of which is connected to an alternating current source 12. The transformer 10 is provided with an additional or supplementary winding 13 of a suitable number of turns which may be determined by experiment. One terminal of the supplementary winding 13 is connected to one side of each of the filaments, and the other terminal is connected through batteries 14 and 15 to the grids and plates respectively. The output circuit of vacuum tube 4 is associated with the input circuit of vacuum tube 5 through the medium of transformer 16, which functions in the well-known manner to pass the output of tube 4 to the input of tube 5. The amplified output of tube 5 is passed through transformer 17 to any suitable indicating device or detector. The transformers 1, 16 and 17 may be either of the audio frequency or radio frequency type, depending upon whether the circuit shown is intended to operate as an audio frequency or radio frequency amplifier.

It is well known that to light the filaments of vacuum tubes in a receiving circuit by alternating current without suitable provision for neutralizing the effects of the alternating current results in the production of a hum in the indicating device which will substantially, if not completely, render the incoming signals indistinguishable. By means of the supplementary secondary winding 13 an alternating potential of predetermined intensity and of the same frequency as that of the source 12 is impressed upon both the grids 7 and plates 8. This potential, which, for convenience, may be referred to as the control potential, operates effectively to neutralize the alternating current hum in the output circuits of the vacuum tubes. It has been found that generally a supplementary secondary winding having approximately half the number of turns of the main secondary winding 9 will produce the desired effect. It is preferable that the windings 9 and 13 be connected differentially as indicated. The control potentials as applied to the grid or plate should, generally, be exactly 180° out of phase with the potential developed by the secondary winding 9 at the terminal to which the supplementary winding 13 is connected. In some instances, it may be necessary to correct the phase relations by the insertion in the circuit of suitable capacity or inductance, but it has not been found necessary to resort to this expedient in the experiments heretofore conducted.

The circuit of Fig. 2 differs from that of Fig. 1 in that the plates, only, are connected to the supplementary secondary winding, while the grid circuits are connected to the respective filaments in the usual manner. In arrangements such as that of Fig. 2, it is usually necessary to make the supplementary winding 13 of a large number of turns, the number being dependent upon the amplification factor of the tubes. For example, if a control potential E applied to the grids would be effective to neutralize the alternating current hum when the amplification factor of the tube is 5, a control potential of approximately $5E$ would be required to be impressed upon the plates in order to produce the same result. Where, however, the control potential is applied to both the grid and plate, a more complex situation arises

on account of neutralization being effected at both cold electrodes.

The arrangement of Fig. 3 is basically similar to that of Fig. 1 in that alternating control potentials are applied to both the grids and plates. 80 For effecting adjustments of the control potential potentiometers 18 and 19 are connected across the terminals of the supplementary secondary winding 13. Each of these potentiometers is provided with two adjustable contacts which are connected respectively to their associated grids and plates. The applied control potential may thereby be separately adjusted for both grids and both plates. Each of the grid circuits is provided in this case with a biasing battery 20 and potentiometer 21.

The circuit arrangement of Fig. 4 is basically similar to that of Fig. 2 in that the alternating control potentials are applied to the plates only. 90 This circuit is also similar to that of Fig. 3 in that a potentiometer 22 having two movable contacts is connected across the terminals of the supplementary secondary winding 13.

The single-tube receiving circuit of Fig. 5 is provided with two transformers 23 and 24 each 100 having a single primary and a single secondary winding. In the particular arrangement shown the number of turns of the secondary windings utilized is variable, but this feature is not at all essential to the proper operation of the circuit. 105 The function of the secondary winding 25 of transformer 24 is the same as that of the supplementary secondary winding 22 of Fig. 4. By the provision of movable contact 26 for effecting connection with a variable number of turns of 110 the secondary 25 and the provision of potentiometer 27, a wide range and great flexibility of adjustment of the alternating control potential is afforded.

In the circuit of Fig. 6 the transformer is provided with two supplementary secondary windings 13 and 28, the first of which provides an alternating control potential for the plates, and the latter alternating control potential for the grids. 115 It is desirable with this arrangement to provide a potentiometer 29, which is shown connected across the terminals of the supplementary secondary winding 28 for adjusting the alternating control potential applied to the grids. Another potentiometer similar to 29 may likewise 120 be connected across the terminals of the supplementary secondary winding 13 for adjusting the alternating control potential applied to the plates. Such provision, however, is not at all necessary and is not shown. The circuit of Fig. 125 6 is characterized by a high degree of flexibility, as well as simplicity, and excellent results have been obtained therewith.

Fig. 7 shows a single-tube receiving circuit comprising an iron core transformer 30 in which 135 the transformer is provided with two air gaps 31 and 32 and a pair of adjusting studs 33 and 34, whereby the widths of the air gaps may be adjusted. By varying the widths of the air gaps 140 the inductive coupling between primary winding 11 and the two secondary windings 9 and 13 may be adjusted, thereby effecting adjustment of the induced potentials in the secondary windings. The various connections are similar to those previously shown and described, and the operation 145 of the circuits is thought to be apparent.

I claim:

1. A system comprising an electron discharge device including anode, cathode and control electrode, an input circuit and an output circuit for 150

- 80 said device, a source of alternating current for heating said cathode, a transformer comprising a primary winding and two secondary windings, said source of alternating current being connected to said primary winding, said cathode being connected across the terminals of one of said secondary windings, the other of said secondary windings being connected to said cathode and at least one of the other of said electrodes jointly, and means for varying the inductive coupling between said primary winding and at least one of said secondary windings, said means being characterized in that it enables the ripple effect in said output circuit to be substantially neutralized upon proper adjustment of said inductive coupling and of the phase relation between the connections of said secondary windings, which ripple effect would otherwise result from a variation of control electrode bias with respect to the alternating potential applied to said cathode.
- 85 2. A system comprising an electron discharge device including anode, cathode and control electrode, an input circuit and an output circuit for said device, a source of alternating current for heating said cathode, a transformer comprising a primary winding and a secondary winding, said source of alternating current being connected to said primary winding, said cathode being connected across the terminals of said secondary winding, and a coil arranged in inductive relation to said alternating current source, one terminal of said coil being connected to said cathode and another terminal of said coil being connected to one of the other of said electrodes, said coil and its connections being characterized in that a current may be derived therefrom which when applied to said electron discharge device tends to neutralize the ripple-effect due to the alternating current by which said cathode is heated.
- 90 3. A system comprising a three-electrode electron discharge device including anode, cathode and control electrode, an input circuit and an output circuit for said device, a source of alternating current for heating said cathode, a transformer having a primary winding and two secondary windings, said source of alternating current being connected to said primary winding, said cathode being connected across the terminals of one of said secondary windings, the other of said secondary windings having one of its terminals connected to said cathode, a resistance element connected across the terminals of the last-mentioned secondary winding, and an adjustable connection to said resistance element, said adjustable connection being connected with one of said electrodes other than said cathode.
- 95 4. A system comprising a three-electrode electron discharge device including anode, cathode and control electrode, an input circuit and an output circuit for said device, a source of alternating current for heating said cathode, a transformer having a primary winding and two secondary windings, said source of alternating current being connected to said primary winding, said cathode being connected across the terminals of one of said secondary windings, the other of said secondary windings having one of its terminals connected to said cathode, a resistance element connected across the terminals of the last-mentioned secondary winding, and a pair of independently adjustable connections to said resistance element, each of said adjustable connections being connected to different ones of said electrodes other than said cathode.
- 100 5. A system comprising a three-electrode electron discharge device including anode, cathode and control electrode, an input circuit and an output circuit for said device, a source of alternating current for heating said cathode, a transformer having a primary winding and two secondary windings, said source of alternating current being connected to said primary winding, said cathode being connected across the terminals of one of said secondary windings, the other of said secondary windings being connected to said cathode and at least one of the other of said electrodes jointly, and means for varying the inductive coupling between said primary winding and said secondary windings, said means being characterized in that it enables the ripple effect in said output circuit to be substantially neutralized upon proper adjustment of said inductive coupling and of the phase relation between the connections of said secondary windings, which ripple effect would otherwise result from a variation of control electrode bias with respect to the alternating potential applied to said cathode.
- 105 6. A system comprising a three-electrode electron discharge device including anode, cathode and control electrode, an input circuit and an output circuit for said device, a source of alternating current for heating said cathode, a transformer having a primary winding and two secondary windings, said source of alternating current being connected to said primary winding, said cathode being connected across the terminals of one of said secondary windings, the other of said secondary windings being connected to said cathode and at least one of the other of said electrodes jointly, and means for varying the inductive coupling between said primary winding and said secondary windings, said means being characterized in that it enables the ripple effect in said output circuit to be substantially neutralized upon proper adjustment of said inductive coupling and of the phase relation between the connections of said secondary windings, which ripple effect would otherwise result from a variation of control electrode bias with respect to the alternating potential applied to said cathode.
- 110 7. A system comprising a three-electrode electron discharge device including anode, cathode and control electrode, an input circuit and an output circuit for said device, a source of alternating current for heating said cathode, an iron core transformer comprising a primary winding and two secondary windings, the core of said transformer being provided with at least one adjustable gap, means for adjusting the width of said gap whereby the inductive coupling between said primary winding and at least one of said secondary windings may be varied, said source of alternating current being connected to said primary winding, said cathode being connected across the terminals of one of said secondary windings, the other of said secondary windings being connected to said cathode and at least one of the other of said electrodes jointly.
- 115 8. The combination with an electrical discharge device having a cathode adapted to be heated, a cooperating anode and a discharge controlling grid, of a source of alternating current, a potentiometer associated with said cathode, circuit elements for impressing across said cathode and potentiometer an alternating potential derived from said source, external circuit connections including said potentiometer between said cathode and anode and between said cathode and grid, means including a transformer having two secondaries whereby compensating currents in phase opposition to one another may be impressed upon the electrodes of said electron discharge device, and means for independently adjusting the connections of the anode and grid to the cathode through said potentiometer to compensate for
- 120 125 130 135 140 145 150

variations in anode potential caused by the heating current of the cathode.

9. In an electron discharge tube apparatus the combination of a thermionic tube having a cathode heated by alternating current, an input circuit and an output circuit for said apparatus, a transformer having a primary winding and a plurality of secondary windings, said cathode being connected across the terminals of one of said second-

ary windings, a potentiometer, said cathode and at least one other electrode of said thermionic tube being adjustably connected to said potentiometer and said potentiometer being connected across the terminals of another of said secondary windings whereby the ripple effect otherwise occurring in the output circuit of said apparatus may be eliminated.
